UNITED STATES PATENT OFFICE.

ROBERT C. BERRY, OF INDIANAPOLIS, INDIANA.

METHOD AND MEANS FOR REMOVING CARBON IN INTERNAL-COMBUSTION ENGINES.

1,230,654.

Specification of Letters Patent. Patented June 19, 1917.

Application filed April 15, 1916. Serial No. 91,427.

To all whom it may concern:

Be it known that I, ROBERT C. BERRY, a citizen of the United States, residing at Indianapolis, Marion county, and State of Indiana, have invented and discovered certain new and useful Improvements in Methods and Means for Removing Carbon in Internal-Combustion Engines, of which the following is a specification.

10 My said invention consists in an improved method and means for removing carbon from the terminals of spark plugs and adjacent parts in internal combustion engines, whereby such result is accomplished without the necessity of removing the plug, and in an inexpensive, efficient, and convenient manner, all as will be hereinafter more fully described and claimed.

Referring to the accompanying drawings, 20 wherein like reference characters indicate corresponding parts,

Figure 1 is a view partly in section and partly in elevation, showing the construction and arrangement of the means employed in a preferred form, and

25 Fig. 2 a detail perspective view of one portion of said means.

In said drawings the portions marked A represent the engine cylinder, B the spark 30 plug, C an injector tube, and D an injector for forcing the carbon remover substance through said tube, all as will be hereinafter more fully described and claimed.

The engine A and spark plug B are, or 35 may be, of any ordinary or preferred type and arrangement and need no special description herein.

The injector tube C is preferably mounted by means of screw-threads in a perforation 40 in the cylinder casing alongside and adjacent to the spark plug. The discharge end, or nozzle thereof, is turned upward at an angle to discharge against the terminals 10 and 11, forming a part of said plug.

45 The upper end of tube C has a valve body 12 mounted thereon by means of a screw-threaded engagement, the lower part of the valve casing being formed with an irregular shaped collar 13, by which it may be 50 turned to position through the medium of an ordinary wrench. A handle 14 is provided for turning the valve, and the upper end 15 of said valve casing is formed to be connected, by means of a short section 16 of 55 a hose, with the discharge end 17 of the injector or force pump D.

Said injector consists of a cylinder D having a reciprocating piston or plunger 20 on the lower end of the piston rod 21, which piston rod runs in a central perforation in a 60 head 22 secured in the upper end of said cylinder. The piston is held in a normally elevated position by a coiled spring 23 interposed between said head and a knob 24 on the upper end of the rod. The plunger is 65 provided with air vent perforations 25 normally closed by a check valve 26 mounted on a screw 27 inserted in the lower end of the piston rod and having a coiled spring 28 for normally holding the check valve closed. 70 Said cylinder is provided with a transversely extending member 29 having a centrally positioned horizontal shelf or support 30 and closed by a thimble-cover 31 that can be secured thereon in any desired manner. A 75 series of perforations 32 are formed through the side of the cylinder D leading into the member 29 both above and below the shelf 30.

The salt S is deposited on said shelf 30, 80 as indicated in Fig. 1, by removing the thimble-cover 31. After the salt is deposited thereon, the cover is replaced and the device is then ready for use by connecting the discharge spout 33 of the member 29, by means 85 of hose 16, with the inlet or upper end 15 of the valve casing 12.

In use, the operator strikes knob 24 sharp, quick blows with the hand, or a mallet, or other implement, which operates to forcibly 90 eject particles of the salt through the nozzle 33, the hose 16, and valve casing, out through the narrow discharge opening of the lower end of pipe C, spraying said salt forcibly against the circuit terminals 10 and 11 and adjacent parts of the spark-plug and cylinder ordinarily covered with carbon. 95 This serves to cut the carbon from said parts. Either at the same time, if the engine is in operation, or subsequently, after the engine 100 is put in operation, the salt itself is dissolved under the heat generated and further serves to clean the cylinder and assist in its efficient operation.

Having thus fully described my said invention, what I claim as new and desire to secure by Letters Patent, is:

1. The combination with an internal combustion engine and spark plug, of a carbon remover device consisting of an injector tube 110 located alongside said spark plug with its discharge nozzle directed to discharge

- against the terminals thereof, a valve for controlling the passage through said tube, and a force feed injector containing carbon remover substance adapted to be connected 5 with said tube, whereby said carbon remover substance may be forced against said terminals, substantially as set forth.
2. A carbon remover device for internal combustion engines comprising an injector 10 tube located alongside the spark plug with its point disposed to discharge against the terminals of said spark plug, and means for forcibly injecting carbon remover substance through said tube under pressure in the 15 form of a spray, substantially as set forth.
3. The method of removing carbon from the terminals of a spark plug or other parts which consists in directing a spray of salt against said parts under pressure, substantially as set forth.
- 20

4. A carbon remover device for internal combustion engines comprising an injector tube located alongside the spark plug with its discharge opening adjacent to the terminals in said spark plug, and a device for 25 forcing carbon remover substance through said injector tube connected therewith and consisting of a cylinder provided with a carbon remover substance container and a plunger for driving said substance through 30 the discharge opening of said tube under pressure, substantially as set forth.

In witness whereof, I have hereunto set my hand and seal at Washington, District of Columbia, this 27th day of March, A. D. 35 nineteen hundred and sixteen.

ROBERT C. BERRY. [L. S.]
